Primary Examiner — Shawn T Gingrich*Assistant Examiner* — Amanda Christensen(74) *Attorney, Agent, or Firm* — Saidman DesignLaw Group, LLC(57) **CLAIM**

The ornamental design for a power charger as shown and described.

DESCRIPTION

FIG. 1 is a front left perspective view of a power charger showing my new design;

FIG. 2 is a front right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict boundaries of the claimed design and form no part of the claimed design; the lightened portions within the broken lines depict portions of the power charger that form no part of the claimed design.

1 Claim, 8 Drawing Sheets(56)
